UNITED STATES PATENT OFFICE.

STAFFORD LIGHTBURNE, JR., OF ST. LOUIS, MISSOURI.

DISTANCE-INDICATOR FOR RAILWAY-CARS.

SPECIFICATION forming part of Letters Patent No. 393,249, dated November 20, 1888.

Application filed May 20, 1887. Serial No. 238,884. (No model.)

To all whom it may concern:

Be it known that I, STAFFORD LIGHTBURNE, Jr., of the city of St. Louis, in the State of Missouri, have invented certain new and useful Improvements in Distance-Indicators for Railway-Cars, of which the following is a full, clear, and exact description, reference being had to the accompanying drawings, forming part of this specification, and in which—

Figure I is a front view of my improved indicator. Fig. II is a top view with part of the casing broken away. Fig. III is an elevation with the front of the casing and one of the push-plates removed. Fig. IV is an end view. Fig. V is a vertical transverse section taken on line V V, Fig. III.

My invention relates to indicators for railway-cars; and my invention consists in features of novelty hereinafter fully described, and pointed out in the claims.

The object of my invention is to provide a box or receptacle in which to place tickets or cards indicating the destination of a passenger, together with the place from where he starts, there being a box located at each seat of the car with two compartments, one for each passenger. When a passenger delivers his ticket to the conductor, it is placed in this receptacle or box, thus indicating the place where the passenger boarded the train and his destination, so that the conductor can always have before him the destination of the passenger, and can readily tell whether the passenger has gone farther than the station to which he has paid his fare, and in case the conductor should be acting in conjunction with a passenger to defraud the company a detective can always tell (it being designed that there should be an order of the company requiring the ticket to be placed in the box with the destination of the passenger indicated thereon, as shown in Fig. I) whether or not the passenger is being carried beyond his station.

Referring to the drawings, 1 is the back plate, 2 the front plate, 3 and 4 the side plates, 5 the top plate, and 6 the bottom plate, forming a casing. The bottom is hinged to one of the sides at 6 $\frac{1}{2}$. These different plates are secured to each other by lugs and rods 8 $\frac{1}{2}$, and thus form a box with the back plate, 1, extending up above the others, on which there may

be cast or printed any desired descriptive matter. The front plate, 2, has openings 2 $\frac{1}{2}$, the use of which will be described hereinafter. The free end of the bottom plate has an extension, 7, in which there is a slot, 7 $\frac{1}{2}$. This slot passes over an extension, 8, of the side plate, 4, this extension 8 having a hole through it in which may be secured a lock, 9, by which the bottom may be locked when it is closed. 55 The box is divided in the center by a partition, 10, one part being a duplicate of the other.

Secured to the back of the box by plates 11 are springs 12 $\frac{1}{2}$, which are bent so that their upper ends extend toward the front of the box, and on which are secured connecting-pieces 12, against which bear push-plates 13, these plates preferably having at top a flange or portion, 14. The top plate, 5, does not extend quite to the front plate, 2, but leaves small openings or slots 15 $\frac{1}{2}$ extending into the interior of the box. Secured to the inside of the top plate, 5, preferably by a fixed plate, 15, are movable plates 16, which come against the front plate, 2, and are held there by means of springs 17 closing the slots 15 $\frac{1}{2}$, the movable plates 16 having extensions or projections 18 that extend into the interior of the box back of and beneath the plates 13. 80

The operation of the device is as follows: Supposing a passenger boards a train at St. Louis, going to Springfield, Missouri. He would hand the conductor such a ticket as is shown on the right-hand side of Fig. I; or if he pays 85 a cash fare the conductor receiving the fare would fill out such a blank as is shown on the left-hand side of Fig. I, and the conductor would then place his ticket or card into the box by pressing against one of the plates 13, 90 forcing it back into the position shown by dotted lines in Fig. V. As he forces the plate 13 back, it comes against the extension of the plate 16, forcing the latter back to open the slot 15 $\frac{1}{2}$. This allows the ticket to be inserted 95 through the slot, and then the conductor removes the pressure from the plate and the springs force it forward, holding the card or ticket against the front of the box on the inside, the ticket being exposed by the opening 100 in the front of the box. As the plate 13 springs forward, the plate 16 is forced forward by the

spring 17, closing the slot, so that the ticket cannot be removed upwardly. When this passenger reaches his destination and gets off the train, the ticket of another passenger entering and taking the seat would be placed in the box in the same manner, the box being capable of holding a number of such tickets, as shown in Fig. V. As already stated, each seat would have one of these boxes or receptacles, or each box or receptacle would have two compartments, so as to hold the tickets for two passengers; or, of course, there could be a separate box for each passenger instead of a double box for the two. When the train reaches its destination, these cards or tickets are removed by an authorized person by taking off the lock 9 and allowing the bottom to swing down, so that the cards or tickets can be taken out downwardly.

20 Each opening in the front of the box or casing is provided with a cross-bar, 25, to prevent the removal of the tickets through the opening.

I claim as my invention—

- 25 1. The combination, with a box having an open front, and a slot near one edge of the box near the front, of a plate adapted to be forced in to allow the tickets which are inserted through the slot to pass in front of it, substantially as shown and described.
- 30 2. In a distance-indicator for railway-cars, the combination of a casing provided with an opening at front through which the ticket may be observed, a spring-plate located within the casing for holding the ticket against the front of the casing, a slot in the top of the casing, through which the ticket may be inserted, and a sliding spring-plate for closing the slot, the latter spring-plate being adapted to be pressed away from

said slot by pressing the former spring-plate 40 to permit insertion of the ticket, substantially as and for the purpose set forth.

3. In a distance-indicator for railway-cars, the combination of the casing provided with an opening in its face, a spring-plate located 45 behind the opening for holding the ticket against the face of the casing, a slot through which the ticket is inserted, a plate for closing the slot, a spring located behind the slot-plate, and an extension on the slot-plate against which 50 the spring-plate impinges, substantially as and for the purpose set forth.

4. The combination of the casing provided with an open front, a spring-plate for holding the tickets against the front, a sliding plate mounted transversely of the casing, for closing a slot at top, a spring engaging the sliding plate for closing the slot, and a downward extension of the sliding plate, against which 55 the top of the first-mentioned spring-plate is 60 adapted to engage, substantially as and for the purpose set forth.

5. In a distance-indicator for railway-cars, the combination of the casing having a slot through which the ticket is passed, a plate closing said slot, a spring located behind the plate, an extension on said plate, a push-plate located 65 within the casing, crossed springs provided with connecting-plates located behind the push-plate, for holding the latter against the front of the box, whereby an even pressure is brought to bear on the push-plate, and a hinged bottom, substantially as and for the purpose set forth.
